UNITED STATES PATENT OFFICE.

JAMES EDWIN HILLS, OF NEW YORK, N. Y.

DESIGN FOR A LINK CUFF-BUTTON.

SPECIFICATION forming part of Design No. 29,562, dated November 1, 1898.

Application filed March 17, 1898. Serial No. 674,268. Term of patent 8½ years.

To all whom it may concern:

Be it known that I, JAMES EDWIN HILLS, a citizen of the United States, residing at New York, in the county of Kings and State of New York, have invented and produced a new and original Design for a Shank and Head for a Link Cuff-Button; and I do declare the following to be a full, clear, and exact description of the same, reference being had to the accompanying drawings, forming a part thereof.

Figure 1 is a side elevation of a shank and head for a link cuff-button embodying my design. Fig. 2 is a front view thereof.

My design consists, essentially, of a curved

shank portion 1, as viewed, in connection with 15 an angularly-disposed head 2, shaped as a flattened ovoid and connected to the shank at or near the inner side of its convergent edge.

What I claim is—

The design for a link cuff-button, as shown 20 and described.

In testimony whereof I affix my signature in presence of two witnesses.

JAMES EDWIN HILLS.
